S. A. NORTH

CARTRIDGE SHELL

Filed March 2, 1921

WITNESS
Frank W. Lommitz Jr.

INVENTOR.
SAMUEL A. NORTH.

BY

A. A. Hickey
ATTORNEY

UNITED STATES PATENT OFFICE.

SAMUEL A. NORTH, OF BRIDGEPORT, CONNECTICUT.

CARTRIDGE SHELL.

Application filed March 2, 1921. Serial No. 449,020.

To all whom it may concern:

Be it known that I, SAMUEL A. NORTH, a citizen of the United States, residing at Bridgeport, in the county of Fairfield and State of Connecticut, have invented certain new and useful Improvements in Cartridge Shells, of which the following is a specification.

This invention relates to cartridge shells and especially to that class which is commonly termed paper shot shells and has for its primary object an improved construction whereby the shell body is effectually interlocked with the base and base wad to prevent the separation of these two parts during the discharge of the shell.

A further object is to provide a gas-tight joint between the various components of the shell so as to prevent the leakage of gases from the shell into the breech chamber or between the base and the base wad as frequently occurs with shells as constructed heretofore.

Another object is to provide a shell of this character the powder chamber of which is formed with a cushioned or padded lining to take up the initial explosion pressure, and to shield the shell proper from the heat of the explosion gases.

A further object is the provision of such a shell having a powder chamber of unusual thickness and strength.

Other objects will appear in the specification which follows; reference being had to the accompanying sheet of drawings which illustrate a preferred embodiment of my invention, in which:

Fig. 1 is a longitudinal section of the various parts for a shell embodying this invention and illustrates the relative positioning of the parts in the process of assembling.

Fig. 2 is a view, partially in section, of a finished shell.

In the drawing, 3 denotes the base, the lower portion of which has a rim 4 forming a circular internal annular recess 5. The base cap 3 has a central aperture 7 through which projects the battery cup 8 containing the primer 9 in the usual manner. Any other usual base would do as well.

The shell body 6' is preferably formed from the usual paper tube by having its lower portion turned back in by a spinning operation into the form seen in Fig. 1 forming the inturned shell 6. This operation re-

duces the density of the body material and causes it to fluff up so that that part of the inturned shell 6 which lines the powder chamber forms an elastic lining for the powder chamber and acts as a cushion for the gases and absorbs any shock that would otherwise have been transmitted directly to the shell and gun chamber. This greatly minimizes the danger of the disruption of the shell or gun and permits of the use of larger and more rapid powder loads.

A further advantage of such a lining, whether elastic or not, is that it shields the material of the shell body proper from the heat of the gases of explosion. The explosion temperature is so high that the shell material is frequently scorched and weakened so that disruption of the cartridge shell may occur. The present invention obviously overcomes this difficulty.

In assembling, the base wad 10, which may be of any suitable construction and material, is inserted into the shell body and the body and wad together are inserted into the base 3. While the base and shell body are confined in a die a punch is brought upon the base wad in the usual way. The wad is compressed longitudinally and expanded transversely whereby that part of the inturned shell 6 which lies adjacent the wad is compressed to substantially its original thickness as shown. However, there is some excess material at the bend in the shell and this forms an internal flange 11 interlocking with the base wad 10 and an external flange 12 interlocking with the internal recess 5 in the base, thus forming an exceptionally strong connection between the shell body and the base and base wad.

The shell is loaded in the usual way as by powder 13, wads 14, shot 15 and a top wad 16 held in place by the crimp 17.

Having described my present invention, what I claim as new and desire to secure by Letters Patent is:—

1. In a cartridge, a tubular shell body, a base, a base wad, and an elastic lining in said shell body extending above said base wad, said lining being integral with said shell body.

2. In a cartridge, a tubular shell body, a base, a base wad and an elastic lining in said shell body extending above said base wad, said lining being integral with said shell body and comprising an inturned extension thereof.

3. In a cartridge, a tubular shell body having an elastic integral inturned portion, a base receiving said shell and formed with an internal annular recess and a base wad 5 expanded into said shell body whereby a portion of said shell body is received in said recess and the body is securely connected with the base.
4. In a cartridge, a tubular shell body 10 having an elastic integral inturned portion, a base receiving said shell and formed with an internal annular recess, integral internal and external flanges formed on said shell body by the doubling over of the material 15 of the inturned portion, said external flange lying in said recess, and a base wad in said shell body formed with an external annular recess receiving said internal flange.
5. In a cartridge, a tubular shell body 20 having an integral inturned portion, a base receiving said shell and formed with an internal annular recess, integral internal and external flanges formed on said shell body by the doubling over of the material of the 25 inturned portion, said external flange lying in said recess, and a base wad in said shell body formed with an external annular recess receiving said internal flange, said inturned
- portion being elastic and extending above said base wad and forming an elastic lining 30 for said shell body.
6. In a cartridge, a tubular shell body having an integral inturned portion, a base receiving said shell, said inturned portion being elastic and forming an elastic lining 35 for said shell body.
7. In a cartridge, a tubular shell body, a base wad, and an elastic protective lining in said shell body extending above said base wad, said lining being integral with said 40 shell body.
8. In a cartridge, a tubular shell body, a base wad, and an elastic protective lining in said shell body extending above said base wad, said lining being integral with said 45 shell body and comprising an inturned extension thereof.
9. In a cartridge, a tubular shell body, a base, a base wad and an elastic protective lining in said shell body extending above 50 said base wad, said lining being integral with said shell body and comprising an inturned extension thereof.

In witness whereof I have signed my name
hereto this 23d day of February, 1921.

SAMUEL A. NORTH.
